INVENTOR;
OZRO N. WISWELL,
BY *Graham Harris*
ATTORNEY'S.

UNITED STATES PATENT OFFICE.

OZRO N. WISWELL, OF LOS ANGELES, CALIFORNIA, ASSIGNOR TO SWINGSPOUT MEASURE CO., A CORPORATION OF CALIFORNIA.

SWING-SPOUT VALVE.

Application filed May 31, 1922. Serial No. 564,743.

To all whom it may concern:

Be it known that I, OZRO N. WISWELL, a citizen of the United States, residing at Los Angeles, in the county of Los Angeles and 5 State of California, have invented a new and useful Swing-Spout Valve, of which the following is a specification.

My invention relates to pouring and flow controlling devices for containers which are 10 used for liquid substances.

It is an object of the invention to provide a swingable spout which may be conveniently mounted upon a container, and which is adapted to be maintained in a retracted 15 flow restricting position over the top of the container, or which may be swung into an extended flow permitting position, in this position the spout serving as a flow directing means in the pouring of liquids into 20 receptacles.

It is also an object to provide a means for sealing the pouring channel provided by the swingable spout and its mounting so that the contents of the container will remain 25 intact during transportation.

It is a further object to provide a means whereby the flow obstructing seal may be readily removed when the use of the contents of the container is desired.

30 The especial advantages of invention and further objects thereof will be made evident hereinafter.

Referring to the drawing which is for illustrative purposes only,

35 Fig. 1 is a perspective view of a container having a swing spout embodying my invention mounted thereupon.

Fig. 2 is an elevation partially in section 40 illustrating the constructional features of the invention.

Fig. 3 is a fragmentary section taken as indicated by the line 3—3 of Fig. 2.

My invention is particularly adapted to 45 use in connection with containers which are employed for containing lubricating oils and other similar liquids and in Fig. 1 I show a square, flat top lubricating oil can 11 having a swingspout 12 mounted thereupon in one corner of the top thereof. This 50 swingspout 12 consists of a tubular pouring member 13 which is so mounted upon the container 11 that it may be swung from the retracted position 15 over the center of the can, in which position a valve closure is formed so that no oil is allowed to pass, to

the extended position over said corner of the can shown at 16 in which position the flow of oil through the pouring spout 13 is freely permitted.

In Fig. 2 of the drawing, the construction 60 of the swingspout 12 is more fully illustrated. In its construction, a circular plate 20 is provided having downwardly turned outer edges 21, and downwardly turned inner edges 22 which encompass a central 65 opening 23 through the plate 20. This plate 20 is adapted to be soldered in the top 24 of a container. A tubular member 26 is vertically mounted in the opening 23 as shown. On the end of this tubular member 70 a closely fitting cup 27 is placed, and the members 26 and 27 are indetachably but rotatably associated by rolling a circular corrugation 28 into both of the members. The pouring spout 13 is secured upon the cup 75 27 and communicates with an opening 29 therein, which opening is adapted to communicate with an opening 30 in the tubular member 26 so that when the openings 29 and 30 are in alignment a free flow from the 80 container through the tubular member 26 and the spout 13 may be obtained. The openings 29 and 30 are shown in alignment in Fig. 2. It will be readily perceived that when the spout is turned into the retracted 85 position 15 shown in Fig. 1 the opening 29 will be disposed in a position opposite to the opening 30, thus providing a closed valve.

It is desirable, during the shipping or 90 storage of containers which are filled with liquids, that these containers be positively sealed so that there can be no escape of liquid therefrom owing to an imperfect fitting of the valve members. In order that 95 this positive closure or seal may be conveniently accomplished I provide a plate 35 comprised of a web 36 having a flange 37 formed around the edge thereof. The plate 35 is pressed into the inner end of the 100 tubular member 26 and may be further sealed therein by dipping the swingspout into a bath of hot paraffine.

It is a further feature of the invention to 105 provide a simple means for removing the closure plate 35 when the use of the contents of the container is desired. This provision I accomplish by the use of a rod 40 which has a head 41 formed upon the upper end and adapted to be received in a depression 110

42 formed in the end of the cup 27, while the lower end of the rod 40 is provided with an enlargement 44 to prevent the rod from being withdrawn from the cup 27. When it is desired to remove the closure plate 35, a pressure is applied to the head 41 of the rod 40 with the thumb or some suitable instrument so that the plate is forced from its position of closure across the lower end 10 of the tubular member 26 and being so dislodged from its position of closure, the plate 35 falls to the bottom of the container and permits the contents thereof to be drawn off through the spout 13 when this spout is in 15 the extended or pouring positions as previously described.

I claim as my invention:

1. An attachment for a container comprising: a stationary tubular member adapted 20 to be secured in an opening of a container and having a discharge opening; a rotatable cap telescopically engaging said tubular member and having a discharge opening adapted to register with the discharge opening 25 of said tubular member; a closure member closing the passage through said tubular member; and means for changing the position of said closure member so as to render the passage through said tubular member

open when force is applied to said means, 30 said means comprising a rod passing through said tubular member and said cap, said rod having an enlarged head protected by a depression in said cap.

2. An attachment for a container comprising: 35 a stationary tubular member adapted to be secured in an opening of a container and having a discharge opening; a rotatable cap telescopically engaging said tubular member and having a discharge 40 opening adapted to register with the discharge opening of said tubular member; a closure member closing the passage through said tubular member; and means for changing the position of said closure member from 45 a temporarily closed position in contact with the tubular member to an open position out of contact therewith so as to render the passage through said tubular member open when force is applied to said means, said means comprising a rod passing through 50 said tubular member and said cap, said rod having an enlarged head protected by a depression in said cap.

In testimony whereof, I have hereunto 55 set my hand at Los Angeles, California, this 23rd day of May, 1922.

OZRO N. WISWELL.
